CLAIM

The ornamental design for a buffing pad, as shown and described.

DESCRIPTION

FIG. 1 is a perspective view of a buffing pad according to the invention.

FIG. 2 is a top view of the buffing pad shown in FIG. 1; and, FIG. 3 is side view of the buffing pad shown in FIG. 1.

The bottom of the buffing pad is not shown because it forms no part of the claimed design.

1 Claim, 2 Drawing Sheets*FIG. 1*

FIG. 2

FIG. 3
